* cited by examiner

(72) Inventor: **Ching-Tsung Lai**, Tainan (TW)

Primary Examiner — Marcus Jackson

(73) Assignee: **Litek Enterprise Co., Ltd.**, Tainan (TW)

(74) *Attorney, Agent, or Firm* — Muncy, Geissler, Olds & Lowe, PLLC

(**) Term: **14 Years**

(21) Appl. No.: **29/449,206**

(57) **CLAIM**

I claim, the ornamental design for an exterior surface configuration of a vehicle lamp, as shown and described.

(22) Filed: **Mar. 14, 2013**

DESCRIPTION

(51) **LOC (9) Cl.** **26-06**

(52) **U.S. Cl.**

USPC **D26/28**

(58) **Field of Classification Search**

USPC D26/28-36; 362/459-468, 475-478,
362/485-487

See application file for complete search history.

(56) **References Cited**

FIG. 1 is a perspective view of an exterior surface configuration of a vehicle lamp showing my present design;
FIG. 2 is a front view thereof;
FIG. 3 is a left view thereof; and,
FIG. 4 is a top plan view thereof.

The broken line showing of the front edge portion of the Vehicle is included for the purpose of illustrating only and forms no part of the claimed design.
